(57) **CLAIM**

The ornamental design for a strobe for camera, as shown and described.

DESCRIPTION

FIG. 1 is a front view of a strobe for camera showing my new design;

FIG. 2 is a rear view thereof;

FIG. 3 is a top plan view thereof;

FIG. 4 is a bottom plan view thereof;

FIG. 5 is a left side view thereof;

FIG. 6 is a right side view thereof;

FIG. 7 is a rear perspective view thereof; and,

FIG. 8 is an enlarged vertical sectional view of the rear dial part cut along the center line of FIG. 2 thereof.

The broken lines are for the purpose of illustrating portions of the strobe for camera that form no part of the claimed design.
